UNITED STATES PATENT OFFICE.

CHARLES C. PRATT, OF WESTFIELD, MASSACHUSETTS.

ORNAMENTAL COVERING FOR UMBRELLA-STICKS, CANES, &c.

SPECIFICATION forming part of Letters Patent No. 242,152, dated May 31, 1881.

Application filed April 6, 1881. (No model.)

To all whom it may concern:

Be it known that I, CHARLES C. PRATT, a citizen of the United States, residing at Westfield, county of Hampden and State of Massachusetts, have invented new and useful Improvements in Ornamental Coverings for the Sticks of Umbrellas, Canes, and other Analogous Articles, of which the following is a specification.

10 This invention relates to ornamental coverings or exterior finish for umbrella-sticks, canes, and other similar articles, applied upon the wood or other material of which they are made, the object being to provide a covering for this class of articles, to be used instead of enamel and similar finishes, and which may with advantage be used instead of ivory in the manufacture of said articles, and whereby the most beautiful ornamental effects may be produced, 15 having a range from pure white to almost an infinite variety of colors, either single or intermingled.

In the drawings forming part of this specification, Figure 1 represents the lower portion 20 of an umbrella-stick having my improved covering applied thereto, by winding it spirally thereon. Fig. 2 represents the upper portion of a cane having my improved covering applied thereto by braiding. Fig. 3 represents 25 a piece of the covering of the stick, Fig. 1; and Fig. 4, a piece of the braided covering, Fig. 2.

In the drawings, *a* is the umbrella-stick. *b* is the handle. *c* is a strip of celluloid. *d* is the head of the cane. *e* is the cane-stick, and *i* represents 30 strips of celluloid applied to the stick *e* by braiding them around it.

My improved umbrella and cane stick covering consists of a thin narrow strip of celluloid wound spirally around them or applied 35 thereto by braiding.

The method of winding is shown in Fig. 1,

and that of braiding in Fig. 2. In the former the celluloid is made in the form of thin narrow strips, and the latter are wound around the sticks, as shown, the ends thereof being 45 properly fastened thereto. This method of preparing and applying celluloid as a covering for the above-named articles admits of producing a great variety of styles of ornamental finish, for, as is well known, celluloid can be had of a 50 color so nearly resembling ivory as to make it nearly impossible to distinguish it from that material; and it can also be furnished in variegated colors in the same strip, and of many brilliant single colors. Thus two or more colored strips may be wound upon said stick, 55 thereby producing a beauty of finish which is unapproachable in appearance and very inexpensive, and as the material is very hard its durability is beyond any similar finish heretofore produced, and it admits of a high polish.

The braided finish or covering shown in Fig. 2 furnishes even a wider range for the intermingling of beautiful colored strips.

The above-described coverings are applicable to whip-stocks, the lower portion of fishing-rods, and a great variety of other articles, as well as to umbrella and cane sticks; and the method herein shown of applying said celluloid coverings permits of such applications with 70 great advantage.

What I claim as my invention is—

The within-described improved covering for umbrella - sticks, canes, and other analogous articles, consisting of a thin strip or strips of 75 celluloid applied thereto by winding or braiding thereupon, substantially as set forth.

CHARLES C. PRATT.
